UNITED STATES PATENT OFFICE.

CHARLES G. PERKINS, OF HARTFORD, CONNECTICUT, ASSIGNOR TO THE
PERKINS ELECTRIC SWITCH MANUFACTURING COMPANY, OF SAME
PLACE.

DESIGN FOR A SNAP SWITCH-BUTTON.

SPECIFICATION forming part of Design No. 31,410, dated August 15, 1899.

Application filed July 20, 1899. Serial No. 724,565. Term of patent 7 years.

To all whom it may concern:

Be it known that I, CHARLES G. PERKINS, a citizen of the United States, residing at Hartford, in the county of Hartford and State 5 of Connecticut, have invented a certain new and original Design for Snap Switch-Buttons, of which the following is a specification.

Referring to the accompanying drawings, which form a part of this specification and which are deemed necessary to an understanding of the design, Figure 1 is a plan of a button formed according to the design. Fig. 2 is a view of the bottom of the button. Fig. 3 is a view of one side, and Fig. 4 is a view 5 looking at the edge of the button.

As shown in the drawings, the leading or material feature of the design consists in the scroll-like appearance of the finger part of the button. In plan the center 1 of the finger part appears swelled, and the wings 2 on each side of the swelled center turn out-

wardly in opposite directions and terminate in lobes 3, which impart the scroll-like effect.

As shown in edge view, the finger part increases in thickness from the top to the bottom without, however, obliterating the scroll-like effect. The center of the bottom 4, although somewhat thicker, is a continuation of the swelled middle of the finger part and extends downwardly in cylindrical form beyond 25 the finger part, and beyond this extends another cylindrical hub 5.

Having described my invention, what I claim as new, and desire to secure by Letters Patent, is—

The design for a snap switch-button as here 35 in shown and described.

CHARLES G. PERKINS.
